CLAIM

The ornamental design for a tip for cigarette, as shown and described.

DESCRIPTION

FIG. 1 is a front perspective view of a tip for cigarette, showing the new design;

FIG. 2 is a rear perspective view thereof;

FIG. 3 is a front view thereof;

FIG. 4 is a rear view thereof;

FIG. 5 is a front perspective view thereof;

FIG. 6 is a rear perspective view thereof;

FIG. 7 is a side view thereof;

FIG. 8 is a side cross-section view taken in the direction of line 8-8 in FIG. 1;

FIG. 9 is a front perspective cross-section view taken in the direction of line 9-9 in FIG. 1; and,

FIG. 10 is a rear perspective cross-section view taken in the direction of line 10-10 in FIG. 2.

The broken lines in the drawing depict portions of the tip for cigarette that form no part of the claimed design.
